TRAVERSING MECHANISM FOR TURRETS

Harold W. Evans, Wilkes Barre, Pa.

Application July 11, 1935, Serial No. 30,860

1 Claim. (Cl. 74—300)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a traversing mechanism for a turret.

The purpose of the invention is to provide a simple and compact turret traversing mechanism in which a clutch is introduced into a 10 system of gearing which includes an actuating handle that is normally secured against rotation.

To these and other ends, the invention consists in the construction, arrangement and combination of elements described hereinafter and 15 pointed out in the claim forming a part of this specification.

A practical embodiment of the invention is illustrated in the accompanying drawing, wherein:

Fig. 1 is a longitudinal sectional view of a 20 traversing mechanism constructed in accordance with the invention.

Figs. 2 and 3 are views on the corresponding lines of Fig. 1.

Fig. 4 is a sectional view showing another arrangement of the clutch.

Referring to the drawing by characters of reference, there is shown a support 5 having a rail 6 whereby a member such as a turret 7 is rotatably mounted through rollers 8.

30 The traversing mechanism for rotating the turret comprises a bracket 9 fixed to the inner wall of the turret and including a gear case 10 which extends underneath a rack 11 on the underside of the rail 6 and is in the form of a trough best shown in Fig. 3.

A shaft 12 extending through the gear case is mounted on antifriction bearings 13—13 and is held in place by a flange 14 on one of its ends and a nut 15 on the other end. The shaft carries 40 a pinion 16 which is mounted on rollers 16a and meshes with the rack 11. The inner side of the pinion is provided with teeth 17 adapted to be engaged by teeth 18 on a clutch member 19 which is slidably mounted on the shaft 12 through 45 splines 20.

The clutch member 19 has the usual groove 21 for the fork 22 of a shifting lever 23. The pivot 24 of the lever is inserted from the bottom of the gear case and the lever extends horizontally of the case. The lever is held in positions of adjustment by a latch 25 which is engageable with a keeper plate 26.

A crank handle 27 is mounted on a pivot pin 28 which passes through apertured ears 29—29 50 formed near the periphery of the flange 14 of

the shaft 12. A spring 30 housed in an axial recess 31 of the shaft normally holds the handle in an inclined position against a stop pin 32. In this position a lug 33 near the free end of the handle is positioned in the opening of a keeper plate 34 fixed to the bracket 9, and the handle is held against rotation. The lug is disengaged from the keeper plate by pressing the handle inwardly. The shifting lever 23 is arranged so that it does not interfere with rotation of the 10 crank handle.

In the modification shown in Fig. 4 a gear case 35 fixed to the turret 36 carries a drive shaft 37 and a driven shaft 38. A sliding gear 39 on the drive shaft is moved into and out of mesh with a spur gear 40 on the driven shaft by means of a shifting lever 41. The lever 41 is disposed in the upper part of the gear case and in either of its two positions of adjustment it does not interfere with a handle 42 on the drive shaft. The 20 particular means for locking this handle against rotation forms no part of this invention and is therefore not shown. The driven shaft 38 also carries a pinion 43 meshing with a rack 44 on a support 45.

In the arrangements shown in both Figs. 1 and 4 the shifting lever is conveniently positioned so that it may be readily grasped by the operator of the crank handle.

Referring to Fig. 1 the turret is normally locked 30 against rotation during travelling by having the clutch 19 engaged with the pinion 16 and the lug 33 of the crank handle 27 engaged with the keeper plate 34. When it is desired to rotate the turret through the gearing the crank handle is 35 pressed inwardly to free it from the keeper plate and it is then rotated. When it is desired to rotate the turret by merely pushing it, the shifting lever 23 is first actuated to disconnect the 40 gearing. The crank handle 27 remains secured and the only operation necessary to again lock the turret is to reengage the gearing.

I claim:

A support having a rack, a turret rotatably 45 mounted on the support, a gear case fixed to the turret and extending underneath the support, a shaft mounted in the case, a pinion loose on the shaft and meshing with the rack, a clutching member keyed to the shaft and slidably into and 50 out of driving engagement with the pinion, a shifting lever for said member, a handle for actuating the drive shaft and means for securing the handle against rotation.

HAROLD W. EVANS. 55
